US00D973813S

(12) **United States Design Patent** (10) Patent No.: **US D973,813 S**
(45) Date of Patent: **** Dec. 27, 2022**

(54) **GOLF CLUB HEAD**

(71) Applicant: **PARSONS XTREME GOLF, LLC**,
Scottsdale, AZ (US)

(72) Inventors: **Robert R. Parsons**, Scottsdale, AZ
(US); **Bradley D. Schweigert**, Cave
Creek, AZ (US); **Michael R. Nicolette**,
Scottsdale, AZ (US); **Caleb S. Kroloff**,
Phoenix, AZ (US); **Matthew T.**
Andrews, Scottsdale, AZ (US)

(73) Assignee: **PARSONS XTREME GOLF, LLC**,
Scottsdale, AZ (US)

(**) Term: **15 Years**

(21) Appl. No.: **29/833,450**

(22) Filed: **Apr. 4, 2022**

(57) **CLAIM**

The ornamental design for a golf club head, as shown and
described.

DESCRIPTION

FIG. 1 is a top perspective view of a golf club head;
FIG. 2 is a bottom perspective view of the golf club head of
FIG. 1;

FIG. 3 is a front elevational view of the golf club head of
FIG. 1;

FIG. 4 is a rear elevational view of the golf club head of FIG.
1;

FIG. 5 is a top view of the golf club head of FIG. 1;

FIG. 6 is a bottom view of the golf club head of FIG. 1;

FIG. 7 is a left side view of the golf club head of FIG. 1; and,
FIG. 8 is a right side view of the golf club head of FIG. 1.
The broken lines shown on the drawings form no part of the
claimed design.

1 Claim, 4 Drawing Sheets

Related U.S. Application Data

continuation-in-part of application No. 29/745,977, filed on Aug. 11, 2020, now abandoned.
